TABLECLOTH

Richard A. Fees, Ardsley, Pa., assignor to Quaker Lace
Company, Philadelphia, Pa.

Filed Feb. 13, 1970, Ser. No. 21,428

Term of patent 7 years

Int. Cl. D6—09

U.S. Cl. D92—26

The figure is a plan view of slightly more than quarter section of the tablecloth showing my new design, the other three sections being identical with the section here disclosed, arranged in proper relation to complete the tablecloth. The section disclosed is shown over a dark background to bring out the details of the design.

The essential feature of the tablecloth resides in the design of the lace edging.

I claim:

The ornamental design for a tablecloth, substantially as shown and described.
